COMBINED LAVATORY AND VANITY

August Felcan, 6N683 Harvey Road, Medinah, Ill.

Continuation of design applications Ser. Nos. 74,072 and
74,073, Mar. 21, 1963. This application July 29, 1964,
Ser. No. 81,403

Term of patent 14 years

(Cl. D4—2)

FIG. 5

FIG. 8

FIG. 7

FIG. 6

FIGURE 1 is a perspective view taken from the front and one side of the combined lavatory and vanity, showing my new design;

FIGURE 2 is an elevational view taken from the other side thereof;

FIGURE 3 is a front elevational view; and

FIGURE 4 is a top plan view thereof;

FIGURE 5 is a perspective view of a modification taken from the front and one side of the combined lavatory and vanity showing my new design;

FIGURE 6 is an elevational view taken from the other side thereof;

FIGURE 7 is a front elevational view; and

FIGURE 8 is a top plan view thereof.

The rear of both forms of the design is open.

The dominant features of my design reside in the portions shown in full lines.

This application is a continuation of my U.S. applications for design for a Combined Lavatory and Vanity,

Serial Nos. 74,072 and 74,073, filed March 21, 1963, both now abandoned.

I claim:

The ornamental design for a combined lavatory and vanity, as shown and described.
